MARION H. WOODWARD, OF BROOKLYN, NEW YORK, ASSIGNOR TO INTERNATIONAL COMMUNICATIONS LABORATORIES, INC., OF NEW YORK, N. Y., A CORPORATION OF NEW YORK

THREE-UNIT, THREE-ELEMENT CODE AND ITS APPLICATION TO SUBMARINE TELEGRAPHY

Application filed January 6, 1931. Serial No. 506,379.

This invention relates to telegraph systems and more particularly to a system for increasing the efficiency of transmission over systems comprising cables connected with land lines.

It is well known in the art that the standard two-element five-unit multiplex code such as used in land line telegraphy is not suitable for use over long submarine cables, because of the inefficiency of the multiplex code in comparison with the standard three-element cable code. The output in letters per minute which may be obtained with the standard three-element code (plus, minus or zero impulses) is in the ratio of

$$\frac{5}{3.7}$$

to the output which may be obtained by using the multiplex two-element code (plus or minus only) with the same signalling frequency applied to the line.

It is also well known in the art that the standard cable code is not as suitable for transmission over land lines as is a two-element code because of the extraneous interference induced into the signalling line from power lines or from other signalling lines. It is usually the practice to operate land lines with a two-element code and to use line currents sufficiently strong to override the extraneous interference. This line interference causes serious trouble in lines operated with the three-unit cable code because during the intervals of the zero impulses in the code, there is no signalling current to override the effect of the interference and thus numerous false signals occur in the system.

A system has been devised whereby a three-unit three-element code transmitted over a cable is automatically translated into a six-unit two-element code for transmission over the connecting land line and whereby a six-unit two-element code transmitted over a land line is automatically translated into a

three-element three-unit code for transmission over a connecting cable. In such a system a short three-element code may be used on the cable which will be more efficient than the standard three-unit cable code in the 50 ratio of

$$\frac{3.7}{3}$$

The connecting land line may also be more efficiently operated, because as a two-element code will be used, the signalling currents will be less affected by extraneous interference. The fact that the six-unit two-element code transmission over the land lines is less efficient in output in letters per minute with the same line frequency than the three-element cable code is not a disadvantage as the operating speed of the entire system is limited by the speed of the cable section, which is usually much lower than the operating speed of the connecting land lines.

The six-unit two-element code may be used at the receiving terminal of the system for operating a two position six magnet printer 70 in a manner well known in the art.

One object of this invention is, therefore, to provide means whereby a six-unit two-element code is automatically translated into a three-unit three-element code for transmission over a cable.

A further object is to provide a system which will automatically translate the received three-unit three-element code into six-unit two-element code for retransmission or for operating a six-unit two position printer mechanism.

A still further object is to provide means for substituting positive and negative current impulses in the two-element code for zero current impulses in the three-element code.

A still further object is to provide means for reversing the above substitution when 90

translating from two-element to three-element code.

A clearer conception of the operation, construction and further objects of the invention may be had from the following specification taken in conjunction with the accompanying drawings in which:

Figure 1 shows a group of similar signals in the six-unit two-element and the three-unit three-element codes.

Figure 2 discloses a translator at the transmitting end of a cable.

Figure 3 shows a translator at the receiving end.

Figure 4 shows a typical line signal using the three-unit three-element code and the same signal translated into the two-unit code.

In Fig. 1 is disclosed a series of characters of the three-unit three-element and the six-unit two-element codes. The characters A, B, C, D and E are in the three-unit code, i. e., each character comprises three impulses of unit length of either positive, negative or zero current. Characters F, G, H, J and K are similar characters in the six-unit code, i. e., each comprising six impulses of unit length of either positive or negative current. It will be noted that characters A and F and B and G correspond, with the exception that the unit impulses of F and G are half the length of the units in A and B. C and H represent the same character in each code and it will be noted that a positive and negative unit of current has been substituted in H for each unit of zero current in C. J and K correspond to D and E with a similar substitution for zero current.

It is apparent from the above that some means must be provided in the translator to substitute zero current in the three-element code for positive and negative impulses in the six-element code.

Fig. 2 discloses a circuit for accomplishing this operation in which 10 is the incoming line and 20 is the outgoing cable. The line relay is shown at 2 and operates in accordance with the line signals, connecting either positive or negative current to the solid ring of receiving segments M of distributor 0, and to the tongue of relay 7. The alternate receiving segments 5 and 6 are connected to the windings of polar relays 7 and 8 respectively and the tongues of these relays transfer the impulses to the operating windings 14 and 15 of the dot and dash locking relays 9 and 11 and thence to the segments 12 of the translating ring N of the distributor. Segments 17 of this ring are unlocking segments for energizing the unlocking windings 18 and 19 of the locking relays. These relays also have biasing windings 21 and 22. Locking windings 23 and 24 are also provided which are under the control of their respective relay tongues. These tongues also control the operating windings

25 and 26 of the dot and dash relays 27 and 28, which in turn control the transmission of impulses to the cable 20.

When a line signal in the six-unit code similar to 29 shown in Fig. 4 is received, the first impulse which is positive causes the line relay 2 to operate, moving its tongue to the spacing contact, thereby closing a circuit from positive battery, solid ring, the distributor brush and segment 5 through the winding of relay 7 to negative battery. This relay will move its tongue to the spacing contact where it will remain until an impulse of opposite polarity is received. The next impulse which is negative will move the tongue of relay 2 to the marking contact and close a circuit through segment 6 to positive battery through the winding of relay 8, which will move its tongue to the marking contact. With the tongue of relay 7 on spacing and the tongue of relay 8 on marking, the circuit for the windings 14 and 15 at relays 9 and 11 is opened, preventing these relays from operating and a zero current impulse is sent out on the cable.

The next unit impulse which is positive again moves the tongue of relay 2 to the spacing contact and a circuit is closed through the second segment 5 operating relay 7, the tongue of which remains on the spacing contact. The next pulse being positive, the tongue of relay 2 remains on the spacing contact and a circuit is closed through the second segment 5 operating relay 8, moving its tongue to the spacing contact.

A circuit is now closed from positive battery on the spacing contact of relay 2 through the tongue and spacing contact of relay 7, spacing contact and tongue of relay 8, windings 14 and 15 of relays 9 and 11, segment 12 and solid ring to negative battery. Since relays 9 and 11 are polar relays and the windings 14 and 15 are oppositely poled, the tongue of relay 9 will move to the marking contact and that of relay 11 to the spacing contact, closing a circuit from positive battery, marking contact and tongue of relay 9, windings 25 and 26 of relays 27 and 28, spacing contact and tongue of relay 11 to negative battery, thereby moving the tongue of relay 28 to its spacing contact and that of relay 27 to its marking contact, and thereby closing a circuit from positive battery, tongue and spacing contact of relay 28, to cable 20, through ground, tongue and marking contact of relay 27 to negative battery thus transmitting a positive impulse to the cable 20. Simultaneous with the closing of the circuit for windings 25 and 26, a second circuit was closed through the locking windings 23 and 24 of relays 9 and 11, holding these relays operated even after the brushes leave segment 12. Positive battery is connected to the cable until the brushes

reach segments 17 when unlocking windings 18 and 19 are energized over a circuit from negative battery solid ring, segment 17, winding 18 and 19 to positive battery. The current in these windings overcomes the effect of the locking windings 23 and 24 and together with the biasing windings 21 and 22 move the tongues of relays 9 and 11 to their spacing contacts, thereby releasing relays 27 and 28 whose biasing windings move their respective tongues to the spacing contacts and remove positive battery from the cable.

The next two impulses being negative, the tongues of relays 7 and 8 both move to the marking contacts and the tongue of relay 9 will remain on its spacing contact while that of relay 11 will move to its marking contact. The tongue at relay 28 will now move to the marking contact while that of relay 27 remains on its spacing contact and negative battery will be connected to the cable until the distributor brush reaches the next unlocking segment 17.

It will be noted from the above that when consecutive pulses of the same polarity are received, impulses of the same polarity are transmitted over the cable and when consecutive pulses of alternating polarity are received, a zero current pulse is transmitted. The resulting signal is shown at 30 (Fig. 4).

In Fig. 3 is shown the circuit for retranslating three-unit three-element signals into six-unit two-element pulses for operating a two position printer 40. The retranslation of the above designated signal 30 into six-unit two-element pulses will be used as an illustration.

The signals are received from the cable 20 by the line relays 31 and 32 which control the operating circuits of the locking relays 33 and 34 through the medium of the regenerating rings R of the distributor 35. Normally the armatures or tongues of the line relays 31 and 32 are held against the spacing contacts, by reason of the energization of the biasing windings b, b as shown. Relays 33 and 34 in turn control the operation of the printer relay 36 which has a second operating winding 37 under control of the translating rings T. The tongue of relay 36 controls a circuit through the selecting rings S for operating three storing relays 41, 42 and 43 which in turn operate the first three printing magnets 44, 45 and 46 and also controls the last three printing magnets 47, 48 and 49. The printer operating magnet 50 is under the control of the local operating rings L.

For the first two impulses of signal 30, which are zero current pulses, the line relays 31 and 32 and the locking relays 33 and 34 remain unoperated. The zero current of the three unit code must be translated into alternate impulses of positive and negative current. This is done by the alternate segments 38 and 39 of the translating ring T first connecting negative and then positive current

through the winding 37 of relay 36, causing its tongue to move first to its spacing contact and then to its marking contact.

When the tongue rests on the spacing contact, a circuit is closed from positive battery through the solid ring and brush of rings S, segment 52, winding of relay 41 to negative battery. This circuit causes the tongue of relay 41 to move to its marking contact, thereby establishing a circuit from positive battery through the winding of printer magnet 44, to segment 59 of rings L. As the brush of the distributor has not reached segment 59 at this time, magnet 44 will not operate. Due to the fact that relays 41, 42 and 43 are polarized relays their tongues will remain on their marking contacts until an impulse of opposite polarity causes the tongue to move to spacing. This maintains the circuit for relay 44, 45 and 46 until the brush associated with rings L reaches segment 59.

The positive impulses from segment 39 of rings T above referred to will now cause relay 36 to move its tongue to the marking contact, closing a circuit for relay 42 from negative battery through segment 53 to positive battery thereby maintaining the tongue of this relay on its spacing contact and no circuit will be closed for the operation of magnet 45.

The next impulse received over the cable according to signal 30 is a positive pulse which will cause relay 31 to move its tongue to marking and relay 32 to move its tongue to spacing, thereby closing a circuit from positive battery through the operating windings 60 and 61 of relays 33 and 34, segment 63 and solid ring of rings R to negative battery. This causes the tongue of relay 33 to move to its marking contact and the tongue of relay 34 to remain on its contact thereby closing a circuit from positive battery through the tongue and marking contact of relay 33, winding 64 of relay 36, spacing contact and tongue of relay 34 to negative battery, thereby causing the tongue of relay 36 to move to the spacing contact and close a circuit from positive battery through the solid ring and segment 54 of rings S for operating relay 43. This causes the tongue of relay 43 to move to its marking contact and establish the circuit for operating magnet 46.

The second part of the positive impulse of the signal holds the relays 31, 32, 33, 34 and 36 in their same positions, thereby closing a circuit through solid ring and segment 55 of rings S for operating magnet 47.

The third portion of the incoming signal which is negative causes relay 31 to move its tongue to the spacing contact and causes relay 32 to move its tongue to the marking contact thereby closing a circuit from negative battery through the operating windings 60 and 61 of relays 33 and 34, moving the tongue of relay 34 to marking and holding

the tongue of relay 33 on spacing. A circuit is now closed from positive battery through the marking contact and tongue of relay 34 through winding 64, spacing contact and 5 tongue of relay 33 to negative battery, causing the tongue of relay 36 to move to its marking contact. As negative battery is connected to both the marking contact of relay 36 and to printer magnet 48, no 10 circuit will be established and thus magnet 48 will not be operated.

In the meantime the distributor brushes have reached segment 59 of rings L, thereby completing the operating circuit for magnet 15 44 and 46 as described above.

The next pulse which is again negative will hold the tongues of relays 31, 32, 33, 34 and 36 on the contacts as described above and magnet 49 will not be operated. When the 20 brush reaches segment 58 of the operating rings L the printer magnet 50 will operate in a well-known manner.

What is claimed is:

1. In a telegraph system, the method of 25 translating from a three-unit three-element code of positive, negative and zero current impulses to a six-unit two-element code of positive and negative impulses by substituting a positive and negative current impulse 30 for each zero current impulse.

2. In a telegraph system, the method of translating from a six-unit two-element code of positive and negative current impulse to a three-unit element code of positive, negative 35 and zero impulses by substituting a zero current impulse for a positive and negative current impulse.

3. In a telegraph system, a pair of stations, a line connecting said stations, means at said 40 first station for translating a six-unit two-element code into a three-unit three-element code of retransmission over said line, and means at said second station for retranslating said three-element code into said two element code.

4. In a telegraph system, a signalling line using a two-element code of positive and negative current impulses, a second line connected to said first line and using a three-element code of positive, negative and zero current impulses, and means at the junction point of said lines for substituting for the alternating impulses of positive and negative current of said first line zero current impulses 55 for transmission of said second line.

5. In a telegraph system, a long signalling line using a three-element code of positive, negative and zero current impulses, a shorter line connected to said first line using a two-element code of positive and negative current impulses, and means at the end of said line for substituting short alternating impulses of positive and negative current for said zero current impulses.

6. In a telegraph system, a pair of stations,

a long line connecting said stations, a translator at one of said stations for translating a three-element code of positive, negative and zero impulses into a two-element code of positive and negative impulses, and means in 70 said translator for substituting short impulses of alternate polarity for said zero current impulses.

7. In a telegraph system, a pair of stations, a long line connecting said stations, a translator at one of said stations for translating a two-element code of positive and negative impulses into a three-element code of positive, negative and zero current, and means in said 80 translator for substituting zero current for impulses of alternate polarity.

8. In a telegraph system, a translator for translating two-element code into three-element code, a line relay controlling the operation of a pair of control relays, a pair of regenerating relays under the joint control of said control relays and a commutator having positive and negative battery connected thereto, a pair of transmitting relays controlled by said regenerating relays and adapted to transmit zero current when consecutive positive and negative impulses are received by said line relay.

9. In a telegraph system a translator for translating two-element code into three-element code, a line relay controlling the operation of a pair of control relays through alternate segments of a commutator, a pair of regenerating relays under the joint control of said control relays and a commutator having positive and negative battery connected thereto, said control relays having their contacts interconnected to supply current of different potential, a pair of transmitting relays under control of said current and being adapted to transmit zero current when consecutive positive and negative impulses are received by said line relay.

10. In a telegraph system, a translator for translating three-element code into two-element code, a pair of line relays, a pair of locking relays operatively controlled by said line relays, a single regenerating relay under the joint control of said locking relays and of a commutator having positive and negative battery connected to alternate segments thereof, said regenerating relay being adapted to transmit short positive and negative impulses when zero current impulses are received by said line relays.

11. In a telegraph system a translator for translating three-element code into two-element code, a pair of line relays, a pair of locking relays having operating windings under control of said line relays and locking windings under control of a commutator, a regenerating relay under the control of said locking relays and a second commutator having positive and negative battery connected thereto, said regenerating 125

relay controlling a plurality of printing magnets through a third commutator and a series of control relays.

12. In a telegraph system a line using six-unit two-element code, a cable using three-unit three-element code, a line relay in said line controlling the operation of a pair of control relays, a pair of regenerating relays under the joint control of said control relays and a commutator, a pair of transmitting relays controlled by said regenerating relays and adapted to transmit three-unit code to said cable, a pair of cable relays, a pair of locking relays jointly controlled by said cable relays and a commutator, and a regenerating relay jointly controlled by said control relays and a second commutator having positive and negative battery connected to alternate segments thereof, said regenerating relay operating a plurality of printing magnets in accordance with the translated three-unit code received by said cable relays.

In witness whereof, I hereunto subscribe my name this 5th day of January, 1931.
